UNITED STATES PATENT OFFICE.

JOHN HAYS HAMMOND, JR., OF GLOUCESTER, MASSACHUSETTS.

PEDAL LOCK.

Application filed November 30, 1925. Serial No. 72,099.

This invention relates to improvements in pedal controls for musical instruments.

The invention has as its main object the provision of a piano pedal for operating certain utilities in a musical instrument of the pianoforte type, and an important feature of the invention is to provide a simple and efficient locking mechanism cooperating with the pedal.

According to one feature of the invention, the utility to be operated may be controlled in accordance with the movement of the pedal to provide for desired musical effects. Another feature of the invention relates to the provision of a pivoted arm having a notch for engaging the pedal to maintain the pedal and the utility controlled thereby in the off-normal position.

Still another feature of the invention relates to the provision of a latch for engaging the free end of the arm to maintain the arm in a desired position with reference to the pedal.

Other objects will appear from the following description taken in connection with the accompanying drawings in which

Figure 1 is an elevation partly in section of a pedal mechanism embodying features of the invention shown in depressed position and with one of the locking devices in locked position;

Figure 2 is a similar view with a pedal in the upper position;

Figure 3 is a section taken on the line 3—3 of Figure 2; and

Figure 4 is a detailed cross section of a portion of the mechanism of Figures 1 and 2 with both locking devices latched.

Like reference characters refer to like parts in the several figures of the drawings.

In the following description and claims, parts will be identified by specific names for convenience of expression, but they are intended to be as generic in their application to similar parts or equivalent construction as the art will permit.

Referring to the drawings there is shown a utility 10 which is to be operated and which may form part of a conventional soft pedal action, sustenuto action or loud pedal action of a piano. The utility 10 is operated by means of a rocking lever 11. The lever 11 is loosely mounted for rotation on a horizontal shaft 12 secured in a conventional pedal block 13. This block 13 may be supported on the lower end of suitable upright

members such as 14 which depend from the body of the piano casing (not shown). The inner end of the lever 11 within the pedal block 13 engages the utility 10 and the outer end 15 is formed to serve as a convenient rest for the foot of the operator.

For normally maintaining the rocking lever 11 in one of its positions as shown in Figure 2, there is provided a spring 20 secured at one end by means of bolts such as 21, and engages at its other end the lower face of the pedal 11. A strip of felt 22 is provided on the block 13 to contact with the upper face of the lever 11, so as to provide a cushion for the pedal in its uppermost position.

A stationary bracket 25 is secured to the lower surface of the pedal block 13 and there is pivotally mounted thereon an arm 26 which extends through a slot 27 in the pedal 11. The arm 26 is provided at one edge with a shoulder or notch 32 which engages the lever 11, as clearly shown in Figure 1. A retractile spring 28 is secured at one of its ends to the lower end of the arm 26, and at its other end to a lug 29 integral with the bracket 25. For engaging the free end of the pivoted arm to maintain the arm in one of its positions, there is provided a secondary latch comprising a bracket 30 secured to the upper portion of the pedal block 13. A secondary catch 31 is pivoted thereto and is arranged to latch the upper end of the arm 26.

The arrangement is such that the foot of the operator can be readily brought into contact with the arm 26 or with the arm 31 as it may be necessary.

In operation, when the rocking lever 11 is depressed at its front end by the foot of the musician, as shown in Figure 1 of the drawings, the utility 10 is raised into operative position. When the rocking lever 11 has been moved sufficiently for the notch or shoulder 32 of the arm 26 to engage the upper face of the rocking lever 11 the arm 26 snaps into place by virtue of the spring 28. In this way the utility may be held in the operated position as long as may be desired without the necessity of the musician maintaining a constant pressure on the rocking lever 11.

When it is desired to release the rocking lever 11, the musician moves his foot into the position shown in Figure 2, thus striking the free end of the arm 26 and disengag-

ing it from the rocking lever 11. The rocking lever may then be moved upwardly under the action of the spring 20, thus restoring the utility 10.

- 5 If the musician desires to use the pedal without its being locked, he pushes the arm 26 into the position shown in Figure 4, until the catch 31 drops over the end of the arm 26. Thus the arm 26 will not engage 10 the rocking lever 11, and the rocking lever may be moved freely under the control of the foot as may be desired. To release the arm 26 the musician lifts his foot to raise the catch 31, thereby allowing the arm 26 15 to be released under the action of the spring 28. Thus it will be seen that an extremely simple device for controlling a utility may be provided. The utility may be operated or released under direct control, or it may 20 be locked in abnormal position. The locking devices are easily operated, and may be selectively controlled by the musician's foot.

The invention upon which this application is based is broader than the specific embodiment shown and described for the purpose of illustrating at least one of the ways in which it may be employed. The scope of the invention is therefore to be understood as not being limited by the present specific description. I intend no limitations other than those imposed by the claims.

What is claimed is—

1. A piano pedal for operating a utility comprising a fixed horizontal shaft, a rocking lever loosely mounted thereon for rotation in a vertical plane, the inner end of said lever being operatively connected to the utility, a spring for normally maintaining said lever in position so that its outer 40 end is at the upper end of its travel, said

lever having a slot, a pivoted arm extending through said slot and having a notch to engage the lever when the outer end of the lever has been depressed, a retractile spring for maintaining the pivoted arm in position 45 so that the notch engages the lever, and a pivoted latch for engaging a free end of said arm to maintain the arm in inactive position.

2. A piano pedal comprising a shaft, a 50 rocking lever rotatably mounted on the shaft, said lever having a slot cut therein, a rod engaging the rear end of the lever, a spring for normally maintaining the lever in the normal position, a stationary bracket, an arm 55 pivoted thereto and extending through the slot of the lever and having a notch for engaging the pedal to maintain the lever in the off-normal position, a retractile spring for maintaining the arm in one position, and a latch for engaging the free end of said arm to maintain the arm in a different position.

3. A piano pedal for operating a utility comprising a rocking lever rotatable in a 60 vertical plane, one end of said lever being operatively connected to the utility, a spring for normally maintaining said pedal in one position, said lever having a slot, a pivoted arm extending through said slot and having 65 a notch to engage the lever when in a different position, a retractile spring for maintaining the pivoted arm in position so that the notch engages the lever, and a pivoted latch for engaging a free end of said arm to maintain the arm in inactive position. 70

Signed at New York in the county of New York and State of New York this 27th day of November A. D. 1925.

JOHN HAYS HAMMOND, JR.
